(57) **CLAIM**

The ornamental design for a beacon light, as shown and described.

DESCRIPTION

FIG. 1 is an isometric front view of a beacon light showing the new design;

FIG. 2 is a front view of the design of FIG. 1;

FIG. 3 is a right side view of the design of FIG. 1;

FIG. 4 is a left side view of the design of FIG. 1;

FIG. 5 is a top view of the design of FIG. 1;

FIG. 6 is a bottom view of the design of FIG. 1;

FIG. 7 is a back view of the design of FIG. 1;

FIG. 8 is an isometric bottom view of the design of FIG. 1;

FIG. 9 is an isometric front view of a second embodiment of a beacon light showing the new design;

FIG. 10 is a front view of the design of FIG. 9;

FIG. 11 is a right side view of the design of FIG. 9;

FIG. 12 is a left side view of the design of FIG. 9;

FIG. 13 is a top view of the design of FIG. 9;

FIG. 14 is a bottom view of the design of FIG. 9;

FIG. 15 is a back view of the design of FIG. 9; and,

FIG. 16 is an isometric bottom view of the design of FIG. 9.

The broken line showing of elements in FIGS. 9–16 is included for the purpose of illustrating portions of the “article” and forms no part of the claimed design.

1 Claim, 16 Drawing Sheets
